UNITED STATES PATENT OFFICE

NELSON WARD HALL, OF SYRACUSE, NEW YORK, ASSIGNOR TO PASS & SEYMOUR, INC.,
OF SYRACUSE, NEW YORK, A CORPORATION OF NEW YORK

DESIGN FOR A LIGHTING BRACKET

Application filed December 5, 1929. Serial No. 33,655. Term of patent 7 years.

To all whom it may concern:

Be it known that I, NELSON WARD HALL, a citizen of the United States, and resident of Syracuse, county of Onondaga, State of New York, have invented a new, original, and ornamental Design for a Lighting Bracket, of which the following is a specification, reference being had to the accompanying drawing, forming a part thereof, and in which:

Figure 1 is a front elevation showing the new design; and

Figure 2 is a side elevation, both figures showing in dotted lines a lamp.

I claim:

The ornamental design for a lighting bracket substantially as shown.

N. WARD HALL.
